(57) **CLAIM**

We claim the ornamental design for an electronic device case, as shown and described.

DESCRIPTION

FIG. 1 is a front perspective view of an electronic device case; FIG. 2 is a front elevational view thereof; FIG. 3 is a back elevational view thereof; FIG. 4 is a left elevational view thereof; FIG. 5 is a right elevational view thereof; FIG. 6 is a top plan view thereof; and, FIG. 7 is a bottom plan view thereof.

The broken lines in the drawings represent stitching and do not form part of the claimed design.
